UNITED STATES PATENT OFFICE.

JOHN EDMAN, OF MINNEAPOLIS, MINNESOTA, ASSIGNOR TO EDMAN CAR DOOR COMPANY, OF MINNEAPOLIS, MINNESOTA, A CORPORATION OF MINNESOTA.

CAR-DOOR LOCK.

1,344,444.

Specification of Letters Patent. Patented June 22, 1920.

Application filed September 4, 1919. Serial No. 321,623.

To all whom it may concern:

Be it known that I, JOHN EDMAN, a citizen of the United States, residing at Minneapolis, in the county of Hennepin and 5 State of Minnesota, have invented certain new and useful Improvements in Car-Door Locks; and I do hereby declare the following to be a full, clear, and exact description of the invention, such as will enable others 10 skilled in the art to which it appertains to make and use the same.

My invention has for its object to provide an improved door locking and clamping means for car doors, such as used on 15 refrigerator cars, and which doors are adapted to be pressed laterally into their seats in the door frame and are generally designated as flush doors.

To the above ends, generally stated, the 20 invention consists of the novel devices and combinations of devices hereinafter described and defined in the claims.

In the accompanying drawings which 25 illustrate the invention like characters indicate like parts throughout the several views.

Referring to the drawings:

Figure 1 is a side elevation showing the 30 central portion of a car body and its door and my improved door locking and clamping means applied thereto;

Fig. 2 is a vertical section on the line 2—2 of Fig. 1;

Fig. 3 is a vertical section on the line 3—3 of Fig. 1; and

Fig. 4 is a vertical section on the line 35 4—4 of Fig. 1, some parts being removed.

The car body is indicated by the numeral 5 and its door, which is of the laterally movable flush door type, by the numeral 6. 40 This door may be supported or hung by any suitable or well known means, not shown. It has been found difficult by a person on the ground to tightly force doors of this type into their seats. Hence, I combine with my improved locking means, a 45 pair of laterally crossed clamping levers 7. These levers 7, at their upper ends, are pivoted to the ends of anchor bolts 8 that are extended through the side of the car ad-

50 jacent to the door opening and preferably above the center thereof, and are swiveled so that the said levers may be moved vertically by swinging movements on the axis

of the anchor bolts 8 as well as laterally on the axis of the pivotal connection between said levers and anchor bolts. 55

At their inner ends, the hanger bolts 8 are shown as provided with nuts 9, but they may be held in position by any suitable means. 60

The two levers 7 are crossed approximately at their central portion, and the one is laterally bent at 7^a so as to clear the other. At their lower ends, the said levers are adapted to be engaged with laterally offset ends of anchor brackets 10 rigidly secured to the car body just below the lower corners of the door. The levers 7, near their lower free ends, are provided with clamping bolts 11 having screw-threaded engagement 65 therewith and provided with heads that bear directly against metallic wearing plates 12 seated in and secured to the outer surface of the door near the bottom thereof. These clamping bolts 11 are provided with laterally bent outer ends by means of which they 70 may be readily turned.

When the levers are engaged with the anchor brackets, as shown in the drawings, the clamping bolts 11 may be tightened and 80 thereby force the lower portion of the door tightly into its seat. As near as practicable to the anchor bolts 8, the door 6, at its edges, is provided with small metallic bearing plates 13 with which the upper ends 85 of the levers 7 engage to tightly force the upper portion of the door into its seat. In this way, the door can be tightly forced into its seat in the car body. When the levers are released, they are adapted to be dropped 90 down into vertical positions indicated by dotted lines in Fig. 1.

The door locking device, which operates on the intermediately crossed portions of the levers 7, comprises a lower lock bracket 95 14 and an upper lock bracket 15. The lock bracket 15, at its lower portion, is bolted, riveted, or otherwise rigidly secured to the car door. The upper portion of said lock bracket 14 is offset from the outer face of the door, so that it will also overlap the crossed portions of the lever 7 when turned downward. It should be noted that the pivoted bracket 15 has a rounded shoulder 15^a which permits the said bracket to be turned 100 105 from an inoperative upturned position

shown by dotted lines in Fig. 1, into the downturned operative position shown by full lines in Fig. 1, and conversely.

The two lock brackets 14 and 15, at their adjacent edges, are provided with perforated offset ears 17 and 18, respectively, through which a lock pin 19 is adapted to be passed, as shown in the drawings. This lock pin 19, advisedly, is connected to the pivot bolt 16 by a short chain 20. The lock bolt 19, at its lower end, has a perforation through which an ordinary car seal 21 is adapted to be passed to hold said lock pin in working position, and to seal the car door so that the latter cannot be opened without detection.

The improved device above described therefore affords, first, efficient means for clamping the door into working position, second, an efficient lock, and third, an efficient sealing device.

What I claim is:

1. The combination with a car body having a laterally movable car door, of clamping and locking means comprising a pair of levers pivoted to the car body adjacent to the sides of the door, said levers being adapted to be brought together at the intermediate portion of the door, and a pair of lock brackets on said door, one fixed and the other pivoted in respect thereto, the said brackets coöperating to lock said levers to said door.

2. The combination with a car body having a laterally movable car door, of clamping and locking means comprising a pair of levers pivoted to the car body adjacent to the sides of the door, said levers being adapted to be brought together at the intermediate portion of the door, and a pair of lock brackets on said door, one fixed and the other pivoted in respect thereto, the said brackets coöperating to lock said levers to said door, and a lock pin insertible through perforations in the said two lock brackets.

3. The combination with a car body having a laterally movable car door, of clamping and locking means comprising a pair of levers pivoted to the car body adjacent to the sides of the door, said levers being adapted to be brought together at the intermediate portion of the door, and a pair of lock brackets on said door, one fixed and the other pivoted in respect thereto, the said brackets coöperating to lock said levers to said door, and a lock pin insertible

through perforations in the said two lock brackets, said pin having a perforated end for application of a seal to hold the same in locking position.

4. The combination with a car body having a laterally movable door, of a pair of levers pivoted at their upper ends to the side of the car body adjacent to the sides of the door opening, the said levers being arranged to be crossed at the intermediate portion of the door, anchor brackets secured to the car body below the door opening and with which the lower ends of said levers are detachably engageable, and means on the door for locking said levers in their overlapped positions, interlocked to the said anchor brackets.

5. The combination with a car body having a laterally movable door, of a pair of levers pivoted at their upper ends to the side of the car body adjacent to the sides of the door opening, the said levers being arranged to be crossed at the intermediate portion of the door, anchor brackets secured to the car body below the door opening and with which the lower ends of said levers are detachably engageable, means on the door for locking said levers in their overlapped positions, interlocked to the said anchor brackets, and door clamping devices applied to the lower portions of said levers for engagement with the lower portion of the door.

6. The combination with a car body having a laterally movable door, of a pair of levers pivoted at their upper ends to the side of the car body adjacent to the sides of the door opening, the said levers being arranged to be crossed at the intermediate portion of the door, anchor brackets secured to the car body below the door opening and with which the lower ends of said levers are detachably engageable, means on the door for locking said levers in their overlapped positions, interlocked to the said anchor brackets, and door clamping devices applied to the lower portions of said levers for engagement with the lower portion of the door, the said levers adjacent their pivots being engageable with the upper side portions of the door to seat the same.

In testimony whereof I affix my signature in presence of two witnesses.

JOHN EDMAN.
